STORAGE CONTAINER FOR SYRUP OR THE LIKE

Bernhard F. Krause, 13 Iolla Court, Bethany, Ill.

Filed July 14, 1961, Ser. No. 65,921

Term of patent 14 years

(Cl. D58—17)

FIG. 1 is a front end elevational view of a storage container for syrup or the like showing my new design;

FIG. 2 is a rear elevational view thereof;

FIG. 3 is a side elevational view thereof; and

FIG. 4 is a top plan view thereof.

The side not shown in the drawings is like the side shown in FIG. 2.

I claim:

The ornamental design for a storage container for syrup or the like, as shown and described.
